UNITED STATES PATENT OFFICE.

HENRY M. SHEER, OF QUINCY, ILLINOIS, ASSIGNOR TO H. M. SHEER COMPANY, OF QUINCY, ILLINOIS, A CORPORATION OF ILLINOIS.

BURNER CONTROL FOR BROODERS AND THE LIKE.

Application filed May 8, 1922. Serial No. 559,438.

My invention relates to an improvement in burner controls for brooders and the like.

The present invention is a valve employed in conjunction with a canopy, burner and oil supply, and made readily accessible to the operator from the outside of the canopy for the perfect control of the oil feed to the flame.

In short, the most important feature of this invention is a valve extending through the canopy in position to be adjusted by the operator while looking at the burner through the canopy.

This invention includes a burner, a stand-pipe from which the burner is supported, a canopy substantially enclosing the stand-pipe and burner, and a valve for controlling the oil passage to the burner, and having a stem extending through the canopy, so that access may be gained to it from the outside of the canopy while the operator is watching the flame of the burner.

This invention further consists in other details that will be described in the more detailed description of the invention.

In the accompanying drawings:—

Fig. 1 is a sectional view.

Fig. 2 is an enlarged view of the valve and surrounding parts.

Fig. 3 is a view similar to Fig. 1 through a cone-shaped canopy, the canopy being shown on a somewhat smaller scale.

A, represents a canopy which may be of cone shape but, for obvious reasons, preferably has a flat top, as illustrated in Fig. 1. The numeral 1 is a hollow casting to which the union 2 is secured. The standpipe 3 extends upwardly from the union to a casting 4 to which it is connected; and this casting is fitted to a hole 5 formed therefor in the top of the canopy.

The valve-seat 6 is seated in the top of the casting 1 and has the transverse openings 6' therethrough, and the valve 7 is screw-threaded and adapted to turn in a thread in the valve-seat for controlling the passage of oil through the longitudinal opening 7' and the transverse openings 6', as shown in Fig. 2.

This valve is extended up through the stand-pipe in the form of a stem 8 to a handle 9 at the top above the canopy by which it is turned from the exterior of the canopy, and a pointer 10 on the stem 8 above the casting 4 indicates the position of the valve

through an index dial on the top of the casting 4, so that it can always be brought back to the exact point at which it was previously set.

A straight pipe 11 screws into the union 2, which extends horizontally to the outer side of the burner 12, as shown in Fig. 1, so that the oil is preheated by the radiation from the burner before entering the oil cup of the latter, and as a means for facilitating cleaning this out, if necessary, the end is closed by a plug 13 screwed into it. By removing this occasionally, the pipe is easily cleaned.

Oil is supplied to a valve, and through the valve to the burner by a pipe 14 leading from the float chamber 15 and the oil reservoir 16 resting thereupon; and this float chamber is raised and lowered by the nut 17 on the screw 18 in order to regulate the level of the oil with respect to the burner, they being normally on approximately the same horizontal plane with each other.

A window 19 fits in the hole 20 immediately over the burner through which the operator can watch the flame when adjusting the valve. The canopy preferably rests on three or more legs 21, and when removing the canopy it is simply lifted from the horizontally extending flange of the casting 4.

By this invention I retain the constant level adjustment at the oil tank, and by means of the adjustment of the nut 17 bring the oil to a predetermined point in the bottom of the oil groove of the burner. The valve 7 is then closed, and the burner is primed and generated as is customary. After the burner is generated, it is possible to control the flame absolutely by means of the valve 7, and with this combination it is possible to maintain a very small flame.

With this combination, it is possible to dispense entirely with vaporizers, because the oil is sufficiently preheated by extending the pipe 11 close to the burner and across to the furthermost side, thereby preheating the oil before it gets to the burner. Carbon formation in the burner is practically eliminated by the use of this construction, and by the elimination of the vaporizer, and any slight accumulation that does take place will be in the pipe 11 beneath the burner, and can be easily removed by unscrewing the plug 13.

By means of the dial on top of the cast-

ing, and the pointer 10, the operator knows just how far to turn the valve. For instance, the valve 7 is closed while generating the burner, as previously stated, and when the burner is ready for the oil the valve is opened until the pointer is at the same number, at which it was previously set, thus giving the identical size of flame as before. By reason of the handle 9 of the valve being located outside of the canopy, it can be adjusted while the operator is looking down through the window 19 into the burner. The flame will always respond instantly to the valve adjustment after the burner shall have been fully generated.

The valve being located beneath the canopy where it is always kept warm, will greatly assist in maintaining a uniform flow of oil.

In Fig. 3, the canopy is shown in the form 23 of a cone instead of with a flat top, the window 19 sloping instead of being horizontal to conform to the shape of the canopy; in other respects this form does not differ in any way from the construction shown 25 in Fig. 1.

I claim:

1. The combination with a canopy, of a burner located beneath the canopy, a stand-pipe connected with the top of the canopy, 30 a support for the burner extending laterally from and carried by the stand-pipe and a valve for controlling the supply of fuel to

the burner having a valve stem extending through the stand-pipe to a point above and exteriorly of the top of the canopy.

2. The combination with a canopy, of a burner located beneath the canopy, a support for the canopy, a support for the burner extending laterally from and carried by the canopy support, a valve for controlling the supply of fuel to the burner having the stem thereof extending through the canopy support and through the top of the canopy, and a window located in the top of the canopy adjacent the valve stem so that the operator can watch the flame at the burner through the window while manipulating the valve.

3. The combination with a canopy, of a burner located beneath the canopy, a stand-pipe connected with the top of the canopy for supporting the same, a support for the burner extending laterally from and carried by the stand-pipe, a valve for controlling the supply of fuel to the burner having a stem extending through the stand-pipe to a point above and exteriorly of the top of the canopy, and a window in the top of the canopy adjacent the valve stem and in a position such that the operator can watch the flame at the burner through the window while manipulating the valve.

In testimony whereof I affix my signature.
HENRY M. SHEER.
